UNITED STATES PATENT OFFICE

JOHAN GUNNAR EVERSTAM, OF SUNDSVALL, SWEDEN

LIFTING JACK

Application filed December 24, 1925, Serial No. 77,578, and in Sweden August 13, 1925.

The present invention relates to a lifting jack of the type in which there is pivotally mounted in the frame of the lifting jack a lever by the reciprocation of which to and fro—
 5 usually up and down—the load is raised and lowered by the intermediary of a feeding pawl pivoted in the lever and which engages a toothed rack slidable up and down in the frame. In lifting jacks of this type as heretofore used, and which have been put to use particularly for lifting motor cars, the raising of the load is effected only when the lever is turned in the one direction, usually downwards. This entails the disadvantage that the
 10 raising of the load requires a comparatively long time, since after each active stroke the lever must be returned idle.

The invention has for its purpose to avoid this disadvantage, and consists principally in
 15 that two feeding pawls are pivoted in the lever on opposite sides of the fulcrum of said lever, said pawls being adapted to engage a toothed rack or the like common to both pawls, and which is slidable in the frame and
 20 serves to carry the load, in such manner that said toothed rack is displaced upon movement of the lever in both directions. Since thus the lever need not be moved idle, the raising of the load may be effected consider-
 25 ably faster.

In the accompanying drawing an embodiment of the invention is illustrated by way of example. Fig. 1 shows a vertical section of a lifting jack according to the invention, and
 30 Fig. 2 shows a horizontal section of the jack on the line II—II in Fig. 1. Figs. 3 and 3^a show the outer long feeding pawl, viewed from two different sides, and Figs. 4 and 4^a show in similar manner the inner short pawl.
 35 Figs. 5 and 5^a show the lever in section and viewed from above respectively, and Figs. 6 and 6^a show, viewed from two different sides, the switch lever which is common to both feeding pawls.

40 In the embodiment illustrated, 1 denotes the frame of the lifting jack in which the toothed rack 2 is movable vertically. The toothed rack 2 supports at its upper end the usual plate 3 which is intended to be placed underneath the load to be lifted, and also at

some distance below the upper end of the rack, a laterally projecting arm 4 which is intended to serve for the same purpose. The rack 2 is provided on one side with teeth 5 with which two feeding pawls 6 and 7 engage, which are adapted to be actuated by means of a handle or the like which is intended to be introduced in the outer sleeve-shaped end 8 of a lever 9 pivoted on a pin 10 in the frame 1. The feeding pawls are pivoted in the lever 9 by means of pins 11 and 12. The feeding pawls are actuated by springs 19 and 20 which tend to turn the pawls to engage the toothed rack. As shown in Fig. 1, the fulcra or pins 11 and 12 of the feeding pawls are located on opposite sides of the fulcrum or pin 10 of the lever 9, so that when the lever 9 is turned for instance in the counter-clockwise direction in Fig. 1, the inner pawl 7 will be raised and the outer pawl 6 will be lowered, whereas the outer pawl 6 will be raised and the inner pawl 7 lowered when the lever 9 is turned in the opposite direction. When the feeding pawls are actuated only by the springs 19 and 20 the toothed rack 2 will thus be moved upwards upon turning the lever 9 in both directions, the movement being effected alternately by the one and the other feeding pawl.

In order to render it possible to lower the load each feeding pawl 6 and 7 is provided at one side with an arm 13 and 14, respectively, which arms project forward to one side of the toothed rack 2, as shown in Fig. 2, and cooperate with a shoulder 15 on the switch lever 16 which is common to both arms. Said lever is pivoted on the pin 10 of the lever 9, at the side of said lever 9, and is actuated by a spring 17 which tends to maintain the switch lever in one of its two extreme positions. The switch lever 16 is provided at its outer end with a handle 18 by means of which it may be turned from one extreme position to the other. Owing to the arms 13 and 14 and the shoulder 15 for the same being located at the side of the toothed rack 2, as above described, the advantage is attained that the pins 11 and 12 of the two feeding pawls 6 and 7 may be located so close to the toothed rack, that the angle between the outer feeding pawl 6 and

the toothed rack 2 will in no case exceed 30° which, as demonstrated by tests, is a necessary condition for the mechanism operating quite satisfactory.

In the position of the different parts shown in Fig. 1, the switch lever 16 is set for lowering the load, the arm 13 of the outer pawl 6 bearing against the shoulder 15. If now it is desired to lower the load, the lever 9 is first turned slightly in the counter-clockwise direction in Fig. 1, with the result that the pawl 6 is slightly lowered so that it becomes free from the load resting on the same, and by the action of the spring 17 and shoulder 15 it will be turned back out of engagement with the toothed rack 2. When the lever 9 is afterwards turned in the clockwise direction in Fig. 1, and the outer pawl 6 is raised, its point or end will therefore move past that tooth 5 with which it was in engagement. Meanwhile, the toothed rack 2 and the load rest on the inner pawl 7, which, while the lever 9 is turned in the clockwise direction, is lowered so that the toothed rack 2 and the load are also lowered. Simultaneously with the pawl 7 its arm 14 is also lowered and meets the shoulder 15 and forces said shoulder slightly downwards. The result is that the outer pawl 6 may, under the actuation of its spring 19, move into engagement with a tooth 5 immediately above the end of said pawl, and take over the load. As soon as this has taken place, the pawl 7 is turned back out of engagement with the toothed rack 2, in the same manner as above described in respect of the pawl 6. When afterwards the lever 9 is again turned in the counter-clockwise direction the outer pawl 6 is lowered and thus also the toothed rack 2 and the load. The course described repeats itself as long as the switch lever 16 occupies the position shown in Fig. 1.

If it is desired again to raise the load, the switch lever 16 is turned by means of the handle 18 in the clockwise direction in Fig. 1 to its other extreme position, in which the lever will be retained by the spring 17 as soon as said spring has passed its middle position. By said turning of the switch lever the shoulder 15 is lowered so far that it will not touch the arms 13 and 14 during the movements of the feeding pawls. Consequently, the feeding pawls are now only actuated by the springs 19 and 20 which tend to maintain said pawls in engagement with the toothed rack 2, and said pawls will therefore alternately operate to raise the toothed rack, each pawl sliding over one tooth when it moves downward.

As shown, the ends or points of the feeding pawls 6 and 7 are rounded, and the bottoms of the spaces between the teeth 5 of the toothed rack 2 are also rounded correspondingly, for the purpose that during the operation of the rack the pawls shall have a sliding engagement with the rack, and the

load be distributed over a large surface on the ends of the pawls. As shown in Figs. 6 and 6^a, the switch lever 16 is provided with a lug 21 with a hole 22 located approximately in the same vertical plane as the middle of the shoulder 15. In said hole 22 the spring 17 is introduced, and it will thus act in substantially the same plane as the arms 13 and 14 of the feeding pawls 6 and 7 when engaging said shoulder 15, any tendency of said arms to tilt the switch lever sidewise on the pin 10 being thus counteracted.

The embodiment above described and illustrated in the drawing is only to be regarded as an example, as it may of course be modified in several ways in respect of its detail without departing from the principle of the invention as described in the accompanying claims.

I claim:

1. In a lifting jack, the combination of a frame, a toothed rack movable in said frame and adapted to support the load, a lever pivoted in said frame, two feeding pawls pivoted to said lever on opposite sides of the fulcrum of said lever and adapted to engage said toothed rack, each of said pawls being provided with a rigid arm, both said arms projecting forward to one and the same side of said rack, and an adjustable switch lever having a shoulder adapted in one position of adjustment of said switch lever to cooperate with said rigid arms on said pawls to move said pawls alternately out of engagement with said rack during the operation of said pawls through said lever.

2. In a lifting jack, the combination of a frame, a toothed rack provided with a row of teeth on its front side and slideable in said frame and adapted to support the load, a lever pivoted in said frame, two feeding pawls pivoted to said lever on opposite sides of the fulcrum of said lever and adapted to engage said row of teeth on said toothed rack, each of said pawls being provided at one side with a rigid arm, both said arms projecting forward to one and the same side of said rack, and an adjustable and spring-actuated switch lever which also projects forward to said one side of the toothed rack and which has a shoulder adapted in one position of adjustment of said switch lever to cooperate with said rigid arms on said pawls to move said pawls alternately out of engagement with said rack during the operation of said pawls through said lever.

3. In a lifting jack, the combination of a frame, a toothed rack slideable in said frame and adapted to support the load, said rack having a row of teeth on its front side, a lever pivoted in said frame, two feeding pawls pivoted to said lever on opposite sides of the fulcrum of said lever and adapted to engage said row of teeth on said toothed rack, each of said pawls being provided at one side

with a rigid arm, both said arms projecting forward to one and the same side of said rack, a spring-actuated switch lever pivoted on the fulcrum of said first-mentioned lever, said switch lever also projecting forward to said one side of the toothed rack and having a shoulder adapted in one position of said switch lever to cooperate with said rigid arms on said pawls to move said pawls alternately out of engagement with said rack during the operation of said pawls through said lever.
